CORE FOR PRODUCING PIPE COUPLINGS
BY ELECTRODEPOSITIONAlfred C. Arbogast, Elkhart, Ind., assignor to
Northern Indiana Brass Company, Elkhart,
Ind.

Application November 23, 1937, Serial No. 176,092

2 Claims. (Cl. 204—6)

This invention relates to improvements in cores for producing pipe couplings by electrodeposition.

The main objects of this invention are:

First, to provide a novel and improved core for use in producing hollow objects of irregular outline, more particularly elbow joint pipe couplings, by electrodeposition.

Second, to provide a core of the type described which is of multiple-part construction to facilitate removal thereof from the finished article.

Third, to provide a core of the type described which is simple in construction and easily and quickly manipulated to assemble and to remove the same from a finished article.

Fourth, to provide a core of the type described of multiple-part construction and having enlarged portions at each end of the same, the parts being adapted to be separated as desired for removing the same from a finished product.

Objects relating to details and economies of the invention will appear from the description to follow. The invention is defined in the claims.

A structure embodying the features of the invention is illustrated in the accompanying drawing, wherein:

Fig. 1 is a view illustrating the multiple-part core of the invention, the parts being in assembled operative relation.

Fig. 2 is a view of the core in longitudinal section, more particularly illustrating the details thereof.

Fig. 3 is a view illustrating the manner of using the core in an electroplating bath.

Fig. 4 is a view illustrating the core partially disassembled in relation to a finished electro-deposited article which is shown in section.

Fig. 5 is a view partially broken away and in section illustrating the completed electroplated elbow fitting produced by the use of the core of this invention.

This invention relates to a core for use in producing hollow objects of irregular or curved outline by electrodeposition. The core shown and described is particularly adapted for the production of elbow pipe fittings and has novel and improved provisions whereby it may be assembled and conveniently removed from such a finished article. However, it will be apparent that the core is not unduly limited in its application and may be employed in producing curved articles other than the elbow fittings referred to.

Referring to the drawing, the reference numeral 1 indicates generally the core of the invention which consists of a central segmental element 2 having an external curvature correspond-

ing to the curvature of the elbow desired to be produced and extending over the major portion of the arc of the elbow. On its inner side, the element 2 is under-cut or truncated at its ends to provide angularly converging faces 3, 4 and a medial inner segment 5 corresponding in its internal curvature to the internal curvature of the fitting to be produced. The portion 5 serves as a locating abutment for supplemental forming elements or sections, indicated by the reference numerals 6, 7. These latter sections are likewise in the form of truncated sections of an angular figure corresponding to the curvature of the segment 5, the sections being provided with angular truncated faces 8, 9 and shoulders 10, 11 respectively complementary to and adapted to abut the faces 3, 4 and the shoulders formed by the segment 5. In properly assembled position, the sections 6, 2, 7 form a completed segment of an annulus corresponding in shape to the shape of the finished article to be produced by electrodeposition.

In order to locate said sections in proper relative position, I provide alining pins 12, 13 on sections 6, 7 respectively adapted to be received in recesses in the element 2, such as are indicated by the reference numeral 14, see Figs. 1 and 4.

Each section 6, 7 has a reduced externally threaded nipple 15 bored and countersunk as indicated generally at 16 to receive a screw 17 for securing sections 6 and 7 to the element 2 which is likewise drilled and threaded internally. On the nipples 15, I provide members 18, 19 which are externally shaped to form the enlarged female coupling ends or sockets of the finished fitting 191, said sockets being designated 20 in Figs. 3, 4 and 5. The said members 18, 19 are drilled and threaded at 21a for threaded attachment to the nipples 15 respectively.

In assembled form, the core 1 appears as illustrated in Figs. 1 and 2. The members 18, 19 are provided with recesses 22 to receive a spanner wrench or other similar tool and they likewise are provided with threaded recesses 23 to receive a suspending member 24, see Fig. 3. The core is first assembled as shown in Figs. 1 and 2 and provided with a uniform coating of suitable conducting material such as graphite, the ends 25 of the members 18, 19 being left uncoated for obvious reasons. The core is then placed in an electroplating bath and a uniform coating of metal deposited thereon.

When finished, the core and fitting produced by electrodeposition are removed from the bath and one or both of the members 18, 19 are re-

- moved by unscrewing the same from its nipple 15. In the case of elbow fittings of certain length or curvature, it may be possible that the rest of the core can be withdrawn without further dismantling the same, i. e., with one or both of the members 18, 19 detached. However, in the event that this is impossible due to the curvature being too sharp, I then unscrew one of the screws 17 to release a section 6 or 7 as illustrated in Fig. 4. 10
10 In the event that the removal of one of the sections is not sufficient to free the core from the inside of the fitting so that it may be withdrawn, the second section may be removed in a corresponding manner, after which it will be found 15 that the central element 2 is readily displaceable from the fitting.

Cores in accordance with my invention may be provided for the electroplating of nearly all types of elbows and obviously the shape and disposition of the faces 3, 4, 8 and 9 is capable of being varied greatly in accordance with particular circumstances. Likewise, the length of the small positioning segment 5 may be reduced or increased so as to allow a greater or less rocking 25 of the central element 2 in the fitting to remove the same. In an event, and without regard to the extent to which the core is to be dismantled to remove the same from the fitting, it will be found that the core produces a fitting which is 30 very smooth externally and internally, the meeting faces of the various sections and elements of the core being capable of machining so as to provide a very smooth exterior for the core.

The recesses 22 facilitate unscrewing of the 35 members 18, 19 by a spanner wrench and if desired the suspending member 24 may be utilized to withdraw the core members from the interior of the fitting.

From the foregoing, it will be apparent that I 40 have provided a core which is adaptable to producing a wide range of types and sizes of elbow joints and other hollow curved objects, regular or irregular and simple or complex in outline. The core is inexpensive and readily manipulated

and is characterized by the excellent results which are obtainable in the finished electrodeposited fitting.

I have illustrated and described my improvements in an embodiment which is very practical. 5 I have not attempted to illustrate or describe other embodiments or adaptations as it is believed this disclosure will enable those skilled in the art to embody or adapt my improvements as may be desired. 10

Having thus described my invention, what I claim as new and desire to secure by Letters Patent, is:

1. A core for producing electrodeposited elbow couplings, comprising an arcuate element having 15 the surface thereof curved in conformity with the curvature of the elbow to be produced, said element being angularly truncated at opposite sides, a plurality of sections adapted to be associated with said element and having curved surfaces 20 complementing the surface of the element when associated relative thereto, means engaging said element and sections for connecting the same and means for completing said core comprising a pair of end members threadedly engageable with said sections, said members and sections being removable to facilitate removal of the core from the finished coupling.

2. A core for producing electrodeposited elbow couplings, comprising an arcuate center element 30 having the surface thereof curved in conformity with the curvature of the elbow to be produced, said element being angularly truncated at opposite sides, a section adapted to be associated at each end of said element and having a curved 35 surface complementing the surface of the element when associated relative thereto, and means for completing said core comprising an end member engageable with each of said sections, said center element and the member and section at one end of the element being removable from one end of the finished coupling. 40
